UNITED STATES PATENT OFFICE

148,705

DESIGN FOR A SET OF EDUCATIONAL CARDS

Shirley Kaufer, Brooklyn, N. Y., assignor to Ed-U-Cards, Inc., New York, N. Y., a corporation of New York

Application February 19, 1946, Serial No. 126,696

Term of patent 7 years

(Cl. D25—1)

To all whom it may concern:

Be it known that I, Shirley Kaufer, a citizen of the United States of America and residing in Brooklyn, New York, have invented a new, original, and ornamental Design for a Set of Educational Cards, of which the following is a specification, reference being had to the accompanying drawing, forming part thereof.

The figure is a face view of the cards of the set showing my new design. The cards are of conventional thickness and the backs are conventional in design.

I claim:

The ornamental design for a set of educational cards, substantially as shown and described.

SHIRLEY KAUFER.
